(57) **CLAIM**

The ornamental design for a dust collection bucket, as shown and described.

DESCRIPTION

FIG. 1 is a front perspective view of the dust collection bucket according to our new design;

FIG. 2 is a front elevational view thereof;

FIG. 3 is a left side perspective view thereof;

FIG. 4 is a right side perspective view thereof;

FIG. 5 is a rear perspective view thereof;

FIG. 6 is a top plan view thereof; and,

FIG. 7 is an upward rear perspective view thereof.

Elements shown in broken line illustrate environment and form no part of the claimed design. Short solid lines indicate surface shading. The dash-dot lines illustrate the boundary of the claim and form no part of the claimed design.

1 Claim, 7 Drawing Sheets
